UNITED STATES PATENT OFFICE

HERBERT ZIKESCH, OF UERDINGEN-ON-THE-RHINE, GERMANY, ASSIGNOR TO BUTTNER-WERKE A-G., OF UERDINGEN-ON-THE-RHINE, GERMANY

BURNER FOR COAL DUST FIRING

Application filed February 9, 1928, Serial No. 253,170, and in Germany February 14, 1927.

The invention pertains to a novel coal dust burner and to a process for operating the same. According to the application, the case of the burner is given such a form and the supply conduits for the air and the coal dust are arranged in such a way that a vortex of materials is produced in the case of the burner, in which there are air and coal dust mixed with each other. In this process the smallest particles are intended to form the core of the whirl and the coarser ones its outermost layers, while an equable combustion of the latter is provided for by enveloping the whole of the coal dust air whirl with an outer air mantle. The formation of the coal dust air whirl may be effected in different ways in accordance with the application, e. g. by conducting a mixture of air and coal dust to the combustion chamber thru a central conduit discharging into the said chamber, while inside the conduit an element, of helical form has been fitted, by which the coal dust air current is made to turn or whirl. This whirling can be caused by air currents tangentially introduced into the combustion chamber, the air currents being preferably conducted in such a way that they will closely pass along the inner wall of the combustion chamber and thus completely envelope the coal dust air whirl like a mantle.

It is particularly important to obtain marked layers in this coal dust whirl. These will be produced, in accordance with the invention, by shaping the combustion chamber in such a way as to enlarge it from the bottom gradually, or rather in form of steps. In this manner a gradual or a sudden expansion of the coal dust whirl in the transverse direction is attained. Thus the coarse particles are thrown outside, while the fine remain in the core of the whirl, from which will result a marked arranging in layers of the coal dust air whirl in conformity with the size of the coal dust particles contained in it. For many purposes, particularly if the formation of a very short coal dust flame should be required, it has proved advantageous to work such a burner with very high degrees of air speed and

pressure far exceeding the speed and pressure hitherto in use. Instead of the speed of about 12 metres at most, as is commonly used for the supply air and corresponds to a comparatively long flame of about 7 to 8 metres, the applicant has advantageously applied, with the new burner, degrees of the speed of 20 metres rising to 50 metres and more a second. This is proportioned to an eduction speed at the nozzles of for instance 20 to 45 metres a second, as compared with 3 to 4 metres with the burner employed up to the present time. In a similar manner the applicant has also raised the excess pressure for instance to 300-400 millimeters and more, in opposition to 150-200 millimeters of the usual operation, while, for the secondary air current, he has appropriately applied a pressure of at least 200 millimeters, against 35-40 millimeters, for the air heater. For this process the blower producing the pressure and supplying the secondary air current is preferably arranged between the air heater and the burner. In this way a smaller difference of pressure is obtained between the smoke gas flues and the air passages than with the usual model, in which the blower was fitted in front of the air heater.

The working of this novel burner with a high speed and a high pressure results in a considerable increase of the efficiency of the burner with the same dimension, as well as in a very short form of the flame, which is but few metres long, that is, 2 to 3 metres. Therefore the operator may render the heating power of this flame serviceable, in many cases, directly from the outlet of the case of the burner, without being obliged to direct the flame round, that is, thru counter-blast currents.

Furthermore the high speed of the supply air current involves the possibility of subjecting this air to a high preliminary heating while excluding the danger of the coal dust flame striking back. For example, with his burner, the applicant has raised the temperatures of the supply air current to about 100° C., with fine coal to 120° C., with coke to 150° C. and more. For the secondary air

current he has even applied degrees of increased temperatures up to 450° C. and has found it to be specially advantageous to supply the secondary air current in steps. The best way is to conduct the secondary air current treated with the highest preliminary heating to the mixture of coal dust and air leaving the burner.

In the subjoined drawings different forms of embodiment of the new burner have been represented.

Fig. 1 shows a burner with a gradually enlarging combustion chamber in its longitudinal section.

Fig. 2 is a cross section according to the line 2—2 in Fig. 1.

Fig. 3 is a longitudinal sectional view of another form of burner.

Fig. 4 is a cross-section taken on line 4—4 of Fig. 3.

Fig. 5 is a longitudinal sectional view of another form of burner showing a stepped arrangement.

Fig. 6 is a cross sectional view taken on line 6—6 of Fig. 5.

Fig. 7 is a longitudinal sectional view of a further modified form of the invention showing particularly a variance of coal dust and air supply.

Fig. 8 is a cross sectional view taken on line 8—8 of Fig. 7.

Fig. 9 is a longitudinal sectional view of another form of the invention, and

Figs. 10 and 11 are respectively a longitudinal section and a cross-section of a further form of the invention, Fig. 11 being taken on line 11—11 of Fig. 10.

In particular, 1 shows the wall of the combustion chamber made of fireproof material, the interior space of the same being enlarged in the shape of a bell towards the rear or discharge opening. At the front end of the combustion chamber the supply of a coal dust air mixture is effected by means of a conduit 2. At the terminal part of this conduit a helical screw 3 is arranged, which serves for setting the coal dust air current passing thru in a rotary and whirling motion.

The combustion chamber is surrounded with a case 4, the interior space of which is separated by a transverse wall 5 into two compartments 6 and 7. Into the latter rooms a secondary air current is introduced thru the conduit 8 and the branch conduits 9 and 10, which current is led tangentially into the interior space of the combustion chamber thru the openings 11, 12, 13, 14 in such a way that the air passes along the interior face of the wall 1, cools the latter and, at the same time, completely envelops the coal dust whirl formed inside. In this way an excellent combustion even of the coarse outer particles of the whirl is warranted.

Following the application, a supplement

ary priming burner, that is, an oil burner of the construction already known may be arranged in the coal dust feeder itself or in the combustion chamber. According to Fig. 1, such a burner is fitted to lie in the axis of the conduit 2. In this case the helical screw 3 is given the form of a spiral-shaped band and the auxiliary priming burner 15 is passed through the interior hollow space at the center thereof.

With reference to Figs. 3 and 4 the reference numbers are applied to the corresponding parts of the burner as in Figs. 1 and 2 and are primed. In this instance the combustion chamber is formed with a square cross section. It enlarges in the shape of a funnel at 16, immediately behind the mouth of the supply conduit 2', then one part of it runs in a straight line, after which it enlarges once more like a funnel at 17. Consequently a double expansion of the coal dust air whirl thus takes place in the enlarged funnel-like part and facilitates the formation in layers of the whirl. Figs. 5 and 6 represent a burner, the cylindrical chamber of which consists of three parts 18, 19, 20 enlarging in stages or steps, the parts corresponding to those shown in Fig. 1 being double primed. In each of the stages an intermittent expansion of the coal dust air whirl takes place, i. e. altogether three expansions within the combustion chamber, the first expansion occurring when the whirl leaves the supply conduit 2'', and the others when it passes into the adjoining graduated rooms of the combustion chamber. In this example of the invention, two auxiliary priming burners are supplied. Preferably the latter should be arranged in such a way that their flame is blowing obliquely or tangentially into the chambers. In this way the auxiliary priming flame, which is blowing in, is caused to contribute equally to the formation of the coal dust air whirl and to envelop the latter or, as it were, to be wrapped up in it, by which process the priming power of the flame is being fully utilized.

Eventually, in this instance as well as in the form of embodiment corresponding to Fig. 1 or in other cases, the shape of the auxiliary priming flame may be measured big enough as to suffice temporarily for maintaining the operation if there should be any interruption and a diminution of the coal dust supply. On the other hand, the auxiliary priming flame may also be put out of use after the ignition of the coal dust air whirl has been started, provided that a further independent burning of the coal dust flame appears to be assured without any auxiliary priming flame, owing to the peculiarity of the coal and to other circumstances.

According to Figs. 7, 8, 9, 23 refers to the wall of the combustion chamber, which enlarges in stages with a stepped gradu-

tion 24 in Fig. 7 and the stepped graduations 25 and 26 in Fig. 9. In this case the coal dust air supply is not effected from the front end, but from the side walls of the combustion chamber and, as may be seen from the cross section in Fig. 8 schematically applying to both Figs. 7 and 9, two coal dust supply conduits 27 and 28 and two compressed air feeders 29 and 30 in each case are alternately arranged round the circumference of the combustion chamber. Air and coal dust will rush into the interior of the combustion chamber thru the openings 31, 32, 33, 34. The said openings are preferably given the shape of transversal slits and lead into the combustion chamber in such a direction approaching the tangent that the band-shaped coal dust and air currents emanating from the openings will, as it were, wind on each other in the form of spiral shaped bands. In this way a coal dust air whirl is produced that is entirely composed of such coal dust and air bands wound or wrapped on each other.

In accordance with Figure 7, an auxiliary priming burner 35 is arranged in the bottom of the combustion chamber. In conformity with Figure 9, also lateral auxiliary priming burners 36 and 37 are provided, beside the auxiliary priming burner 35 fitted in the bottom of the combustion chamber, which burners may enter obliquely or tangentially, so that their flame is wrapped up inside the coal dust air whirl.

After Figs. 10 and 11, the combustion chamber 38 is supplied with a stepped graduation 39 and surrounded with a casing 40. Four coal dust supply conduits 41, 42, 43, 44, which open into the longitudinal slits 45, 46, 47, 48 introduced tangentially into the combustion chamber, are passing thru the said casing. By means of the conduits 49, 50 the casing 40 is provided with compressed air rushing into the different compartments of the combustion chamber thru the air slits. With this form of embodiment too, a coal dust air whirl is obtained which consists, as it were, of bands and air bands wound or wrapped on each other. Moreover, a coal dust air mixture likewise set in a whirling motion and forming the core of the flame is conducted thru a conduit 51 to the bottom of the combustion chamber, in which conduit lies a piece of a screw face 52. An auxiliary burner 53 fitted in the axis of the supply conduit 51 manages the priming of the coal dust flame.

The forms of embodiment described may be varied in manifold ways within the scope of the leading ideas of the invention. In each case, the due formation in layers of the coal dust air whirl thru the expansion obtained by means of a gradual or step-like enlargement of the combustion chamber is of first consequence.

I claim:

1. A coal dust burner in which combustion is entirely effected, including a burner body which is widened and enlarged in step-wise formation from one end to the other, a longitudinally extending inlet conduit communicating centrally with the small end of the body, means in said inlet for forcibly introducing a whirling mixture of primary air and coal dust centrally of the burner body, the walls of the body being provided in each of the stepped portions with tangentially arranged air admission openings through which secondary air is admitted to form a closed layer of air adjacent the walls of the burner.

2. A burner as claimed in claim 1, wherein a secondary air containing casing is provided about the stepped burner body and is provided with partitions forming separate compartments for dividing the said secondary air casing into compartments corresponding to the stepped portions of the body, and means for supplying secondary air to each of said compartments.

In testimony whereof I affix my signature.
HERBERT ZIKESCH.
